U.S. Cl. D23—40

Fig. 1.

Fig. 2.

Fig. 3.

Fig. 4.

FIG. 1 is a top plan view of a valve guide for flush tanks, showing my new design, the bottom being essentially the same as the top shown;

FIG. 2 is an elevational view of one side thereof, the opposite side being identical to the side shown;

FIG. 3 is an elevational view of one end thereof; and

FIG. 4 is an elevational view of the end opposite that shown in FIG. 3.

I claim:

The ornamental design for a valve guide for flush tanks, substantially as shown and described.
